UNITED STATES PATENT OFFICE.

STEPHEN A. DOBYNE, OF ST. LOUIS, MISSOURI, ASSIGNOR TO CHAMPION SHOE MACHINERY COMPANY, OF ST. LOUIS, MISSOURI, A CORPORATION OF MISSOURI.

NEEDLE-GUIDE-OPERATING MECHANISM FOR SEWING-MACHINES.

1,233,992.

Specification of Letters Patent. Patented July 17, 1917.

Original application filed March 12, 1913, Serial No. 753,751. Patent No. 1,201,160, dated October 10, 1916.
Divided and this application filed March 22, 1916. Serial No. 85,791.

To all whom it may concern:

Be it known that I, STEPHEN A. DOBYNE, a citizen of the United States, and residing at St. Louis, in the State of Missouri, have 5 invented a certain new and useful Improvement in Needle-Guide-Operating Mechanism for Sewing-Machines, of which the following is a specification.

This invention relates to sewing machines 10 and more particularly to the needle guide operating mechanism therefor.

One object of this invention is to provide novel mechanism for operating the needle guide, whereby this needle guide will be operated positively in both directions.

Further objects will appear from the detail description taken in connection with the accompanying drawings, in which:

Figure 1 is a side elevation of the sewing 20 machine embodying this invention;

Fig. 2 is a detail side elevation of the needle guide operating means;

Fig. 3 is a front elevation; and

Fig. 4 is a section on the line 4—4 Fig. 2, 25 parts being shown in elevation.

Referring to the accompanying drawing, 15 designates a column upon which is mounted a head or base 16, having a pair of brackets, one of which is shown at 18 for supporting the drive shaft 19. A series of cam wheels, one of which is shown at 23, are keyed to the drive shaft. A needle 29 is mounted in a lug 109 on the head or base 16, and this needle is provided with the usual 30 needle guide 115. The parts so far described are fully disclosed in my co-pending application, Serial Number 753,751, filed March 12, 1913, which matured as Letters Patent 1,201,160, dated October 10, 1916, and of 35 which the present application is a division.

40 A bell crank lever 95 is mounted on a shaft 110 journaled in the bracket 18 and this lever has one arm provided with a cam roll 96 co-operating with the cam groove 97 in the cam wheel 23. The other arm of the bell crank lever has a tooth 98 meshing with teeth 99 on a lever 100 pivoted at 111 intermediate its ends on the lug 109 on the ma-

chine head, and having at its other end teeth 101 meshing with a gear segment 102 on a 50 shaft 112 mounted in the lug and having a gear 113 meshing with teeth 114 on the needle guide 115. The teeth 98 and 99 are shaped to form the teeth of a bevel gear.

The needle guide operating mechanism 55 described is especially adapted for assemblage, together with the other mechanisms, in the machine disclosed in the above noted application, while the provision of the lever 100 co-operating with the bell-crank lever 95 60 permits of the cam groove 97 being formed in the periphery of the cam wheel 23, thereby placing said groove at a point farthest removed from the shaft 19 and adapting the cam to exert its maximum force in actuating 65 the mechanism which operates the needle guide.

The operation of the needle guide is positive and it is, therefore, insured that it will 70 be in correct timed relation with respect to the needle. The operating mechanism is so arranged as to avoid interference with the other mechanisms of the machine. This mechanism is, therefore, characterized by simplicity of construction and certainty of 75 operation.

It is obvious that various changes may be made in the details of construction without departing from the spirit of this invention, and it is therefore to be understood that this 80 invention is not to be limited to the specific construction shown and described.

Having thus described the invention, what is claimed is:

1. In a sewing machine, a needle guide, 85 and operating means for said needle guide comprising a pair of toothed levers in mesh one with the other pivoted one at right angles to the other.

2. In a sewing machine, a needle guide, a 90 lever connected to said needle guide, a bell crank lever connected to operate said first named lever, and a cam for operating said bell-crank lever.

3. In a sewing machine, a needle guide 95 having a gear segment, a gear meshing

therewith, a lever connected with said gear, and an operating lever having a toothed connection with said first named lever.

4. In a sewing machine, a head having a shaft supporting bracket, a needle guide supporting bracket, a needle guide supported thereby, a lever geared to said needle

guide and supported on said last bracket, and an operating lever geared to said first named lever and supported on said first bracket. 10

In testimony whereof I affix my signature this 3 day of January, 1916.

STEPHEN A. DOBYNE.
